ELECTRIC SWITCH

Leslie Day, Chicago, Ill., assignor of one-half to
Lamar L. Day, St. George, N. Y.

Application October 22, 1945, Serial No. 623,812

7 Claims. (Cl. 200—155)

1

This invention relates to switches generally and more particularly to electric switches for use in electrical systems for controlling the brakes of railroad trains, this application being a division of applicant's copending application for Control Systems, Serial No. 453,872, filed August 6, 1942, now Patent No. 2,391,228, December 18, 1945.

An object of the invention is to provide an electrical switch which may be attached to railroad cars and so positioned as to be actuated upon derailment of said cars and to thereby control the electrical brake control system.

Another object of the invention is to provide a device of this character having a control member adapted to be positioned so as to strike a rail and be actuated upon derailment of the car.

Still another object of the invention is to provide a device of this character having yielding means incorporated therein which will generally prevent injury to the switch when the control member strikes a rail and is actuated.

Still another object of the invention is to provide a device of this character of simple construction and operation and that is sturdy and reliable.

Other objects and advantages of the invention will be apparent to those skilled in the art from the following description or may be ascertained from a study of the accompanying drawings in which one embodiment of the invention has been shown. It will be evident that the principles of the invention may be incorporated in various forms and I contemplate the employment of any structures, arrangements, or modes of operation that are properly within the scope of the appended claims.

In the drawings:

Figure 1 is an end view, partly in section, of a switch embodying the invention;

Figure 2 is a view of same, partly in section, taken at right angles relative to Figure 1; and

Figure 3 is a sectional view taken on line 3—3 of Figure 1.

Referring to the drawings there are a pair of U-shaped frame members 10 secured to the spring plate 11 of a railroad car, not shown, by bolts 12. The members 10 are spaced apart and receive therebetween a movable switch member including a body portion 14 having laterally extending shafts 16 pivoted in respective frame members 10. The end portion of each shaft 16 is provided with a sleeve 18 of electrical insulating material such as "Bakelite" or the like. Within the member 14 is a pipe 19, each end of which is threaded

and projects outwardly longitudinally of said body 14. Caps 20 and 22 are screwed on the upper and lower ends respectively of said pipe and said caps abut against respective adjacent ends of the body 14. Cap 20 is provided with a square opening in which is slidably received a rod 24 which is square in cross section, said rod having a head 26 within the pipe 19 and is adapted to slide freely therein. A spring 28, reacting against cap 20 and head 26, yieldingly urges rod 24 outwardly. The lower end of rod 24 is provided with a block 30 of steel or other suitable material, which is received on a reduced portion 32 of rod 24. The free end of the reduced portion 32 is overturned at 34 for retention of said block on rod 24.

Semi-circular electrical contact members 36 are disposed adjacent opposite sides of the movable switch member. The semi-circular members 36 include lateral arms 38 adjacent to the respective ends thereof, said arms having end portions 40 secured to respective frame members 10 by bolts or screws 42, thus holding said contact members in position and grounding them to the frame of the car through frame members 10 and spring plate 11.

The contact members 36 are disposed in parallel planes between which the switch member is adapted to swing, and the radius of said contact members 36 coincide with the radius of the path of the upper end of said switch member. The positioning and spacing of the contact members 36 is such that when the switch member swings from a vertical position the upper end thereof, which is shown as comprising the cap 20, will contact same. However, to prevent contact between the switch member and the contact members when the former is in a vertical position, said contact members are provided with central U-shaped portions which extend outwardly and in which blocks 44 are secured by screws 46 or by any other suitable means. The blocks 44 are of "Bakelite," fibre or other suitable electrical insulating material and have opposed concave portions 45 in which the cap 20 is received, the resilience of the contact members urges the blocks 44 against the cap 20 and normally retains the switch member in its vertical position.

A wire 47 of the electrical circuit is secured to the body 14 by a screw 48. Inasmuch as the switch member is insulated by sleeves 18 from the frame members 10, no electric current will flow through the switch when the switch member is in the vertical position wherein the cap 20 is

held against contact with the contact members 36 by the blocks 44.

The switches of the embodiment shown are located on the spring plates with the blocks 30 located above the top plane of the rails and outwardly thereof. Considering a single switch, upon derailment of a car carrying said switch, the block 30 thereof will strike the top or ball of the rail, not shown. The rod 24 is forced upwardly, compressing the spring 28 which absorbs the resulting shock. At the same time the forward motion of the car will cause the movable switch member to swing as indicated by the dotted line 52 in Figure 1. The upper end of the switch member will swing into contact with the contact members 36 and complete the circuit through the switch thus closing the control circuit of the train which in turn effects operation of the main circuit and the application of the brakes as fully described in the above referred to application, Serial No. 453,872.

In order to use a switch of this character in a closed circuit system it would be necessary to arrange the contact members so that when the movable switch member is vertical there would be an electrical contact between members 36 and said movable switch member, and when said switch member is swung out of the vertical position the electrical contact would be broken.

If desired, a casing or cover 54 may be provided to enclose the switch and said casing may be secured by indentations 55 therein which engage the upper edge of the lower horizontal portions of the frame members 10. A slot 58 is then provided in the bottom side of the casing in which the depending portion of the movable switch member is received, said slot being wide enough to prevent contact of the switch member with the sides thereof and long enough to permit swinging of the switch member for completion of the circuit through the switch.

It will be understood that many variations of the invention can be made from the disclosed embodiment and it is not intended that the scope thereof shall be limited to the form shown and described, nor otherwise than by the terms of the appended claims.

I claim:

1. In an electrical switch for the circuit of an electrical system for controlling the application of brakes of railroad trains: a frame; a hollow swingable member pivotally mounted in the frame and having an annularly shaped head adjacent the upper end; a plunger having a portion thereof adapted to be slidably received in the depending end of said hollow swingable member, said plunger normally extending outwardly of the lower end of said member; yielding means adapted to urge the plunger to its outward position and cushion sudden inward movement thereof; a pair of resilient arcuate shaped contacts spaced apart and disposed on opposite sides of the head of said swingable member, said contacts having a radius substantially coincidental with the path of said head and adapted to be slidably contacted by said head when the latter swings in either direction from a substantially vertical position, and each of said contacts having a centrally U-shaped outwardly extending offset portion; and a piece of insulating material secured in each of said offset portions, the inner faces of said insulating pieces being concave for the reception of the head of said swingable member and for releasably retaining said swingable member in a substantially vertical position when

the switch is operably mounted on a train unit.

2. The invention defined by claim 1, wherein the plunger is provided with a cross member adjacent the lower free end thereof.

3. In an electrical switch for the circuit of an electrical system controlling the application of air brakes on a railroad train: a frame; a hollow swingable member pivotally mounted in the frame; a plunger having a portion thereof adapted to be slidably received in the hollow swingable member, said plunger normally extending outwardly of one end of said member; a part adjacent the free end of said plunger adapted to contact the rail of a track upon derailment of the train; yielding means adapted to resist inward movement of the plunger; a resilient contact member of substantially arcuate shape adjacent the opposite end of the swingable member; insulating means for releasably holding the swingable member in a predetermined position out of electrical contact with the contact member, said insulating means being yieldably urged against said swingable member by said contact member and said swingable member being adapted to be swung to another position whereat it makes an electrical contact with said contact member; and means for insulating one of said members from the frame.

4. In an electrical switch for the circuit of an electrical system for controlling the application of brakes of railroad trains: a frame; a hollow swingable member pivotally mounted in the frame and having an annularly shaped head adjacent the upper end; a plunger having a portion thereof adapted to be slidably received in the depending end of said hollow swingable member, said plunger normally extending outwardly of the lower end of said member; yielding means adapted to urge the plunger to its outward position and cushion sudden inward movement thereof; a pair of resilient arcuate shaped contacts spaced apart and disposed on opposite sides of the head of said swingable member in planes parallel to the path of movement of said swingable member, said contacts having a radius substantially coincidental with the path of said head and adapted to be slidably contacted by said head with a wiping action when the latter swings in either direction from a substantially vertical position, and each of said contacts having a centrally U-shaped outwardly extending offset portion; and a piece of insulating material secured in each of said offset portions, the inner faces of said insulating pieces being concave for the reception of the head of said swingable member and for releasably retaining said swingable member in a substantially vertical position when the switch is operably mounted on a train unit.

5. In a self contained electrical switch: a frame wherein is a pivoted lever contact member having a yielding telescoping part; a fixed switch part including a resilient generally arcuate fixed contact member having a generally U-shaped portion; and insulating means secured in said U-shaped portion, said switch part being biased toward the pivoted contact member to frictionally maintain the status quo of an electric circuit when established by external means actuating said pivoted contact member to a position whereat it contacts said fixed contact member.

6. In an electrical switch for the circuit of an electrical system for controlling the application of brakes of railroad trains: a frame having a pivoted contact member including a yielding telescoping part; a fixed switch part including a resili-

ient generally arcuate fixed contact member having a generally U-shaped portion; insulating means secured in said U-shaped portion, said switch part being biased toward the pivoted contact lever to frictionally maintain the status quo of an electric circuit when established by external means actuating the pivoted contact member to a position whereat it contacts said fixed contact member; and a cross member secured adjacent the outward end of the yielding telescoping part, said cross member being positioned transversely to the path of movement of the pivoted contact member.

7. In an electrical switch for an electrical system controlling the application of air brakes on a railroad train: a support; a swingable contact member pivotally mounted on the support; a plunger telescopically associated with said swingable contact member; a part adjacent the free end of said plunger adapted to contact a track rail upon derailment of the train; yielding means adapted to resist telescoping movement of the plunger; means, including a fixed resilient electric current conducting contact member and insulating means carried thereby for insulating a part of the contact member from the swingable member, said contact member being disposed adjacent the opposite end of the swingable member and being substantially arcuate in shape with the radius substantially coincidental with the path of movement of said opposite end of the swingable member, said means being biased against said opposite end of the swingable mem-

ber and being so constructed and arranged as to provide a recess for reception of said opposite end of the swingable member for releasably retaining same in one position, said opposite end of the swingable member being in electrical contact with said fixed contact member when in one position and insulated therefrom by the insulating means when in another position and being frictionally restrained from movement by the resiliency of the fixed contact member when moved to a position outside of said recess by external force.
